(Cl. D81—2)

To all whom it may concern:

Be it known that I, Rallston M. Sherman, a citizen of the United States and a resident of Glastonbury, county of Hartford, State of Connecticut, have invented a new, original, and ornamental Design for Oil Burner Unit, of which the following is a specification, reference being had to the accompanying drawings, forming part thereof.

In the drawings:

Fig. 1 is a front elevational view of an oil burner unit, showing my new design;

Fig. 2 is a side elevational view of the unit as viewed from the right of Fig. 1; and

Fig. 3 is a side elevational view of the unit as viewed from the left of Fig. 1.

I claim:

The ornamental design for an oil burner unit, substantially as shown.
